(57) **CLAIM**

The ornamental design for a magnifier stand, as shown and described.

DESCRIPTION

FIG. 1 is a perspective view of a magnifier stand showing my new design;

FIG. 2 is a front view thereof;

FIG. 3 is a rear view thereof;

FIG. 4 is a right end view thereof;

FIG. 5 is a left end view thereof;

FIG. 6 is a top view thereof;

FIG. 7 is a bottom view thereof;

FIG. 8 is a perspective view thereof, shown in an extended position; and,

FIG. 9 is a perspective view thereof, shown being in-use with a magnifier.

The broken lines in the drawings depict a magnifier that forms no part of the claimed design.
